APPARATUS FOR CONTINUOUSLY COILING
ELONGATED FILAMENTSEstyle D. Hanson, Baltimore, Md., assignor to
Western Electric Company, Incorporated, New
York, N. Y., a corporation of New York

Application March 31, 1947, Serial No. 738,443

16 Claims. (Cl. 242—80)

1

This invention relates to apparatus for continuously coiling elongated filaments, and particularly to apparatus for continuously coiling conductors into a series of coils and for severing the conductors to separate coils.

In the manufacture of filamentary articles, such, for example, as jacketed or insulated conductors, wherein filamentary articles are formed or processed continuously by suitable apparatus and are advanced from the apparatus continuously, the elongated articles frequently are coiled and severed into a series of coils. In the past, no apparatus has been provided for easily coiling such articles into a series of coils without stopping the processing apparatus at intervals to sever the article when a coil of the desired length is formed and to attach the severed end of the article to some sort of alternate apparatus for forming a new coil.

An object of the invention is to provide new and improved apparatus for continuously coiling elongated filaments.

A further object of the invention is to provide new and improved apparatus for continuously coiling filamentary articles into a series of coils, and for severing portions of the articles extending between the coils to separate the coils.

An apparatus illustrative of certain features of the invention includes a series of coiling elements, which are indexed so that only one set is operative at one time to form a coil from a filamentary conductor. After a predetermined length of the conductor is coiled on one set of coiling elements, the coiling elements are indexed to bring another set of coiling elements into position to coil the conductor. One of the coils previously formed is dropped onto a pan of a turntable and is severed from the remainder of the coils by an automatic cut off device. The turntable then is rotated to move an empty receiving pan into a coil-receiving position, and the operations described hereinabove are repeated.

A complete understanding of the invention may be obtained from the following detailed description of an apparatus forming a specific embodiment of the invention, when read in conjunction with the appended drawings, in which:

Fig. 1 is a fragmentary, top plan view of an apparatus embodying the invention;

Fig. 2 is an enlarged, fragmentary side elevation of the apparatus with portions thereof shown in section;

Fig. 3 is an enlarged, fragmentary, horizontal section taken along line 3—3 of Fig. 2;

2

Fig. 4 is an enlarged, fragmentary, horizontal section similar to Fig. 3 but with certain elements of the apparatus shown in different positions;

5 Fig. 5 is an enlarged, fragmentary, vertical section taken along line 5—5 of Fig. 2;

Fig. 6 is an enlarged, vertical section taken along line 6—6 of Fig. 2;

10 Fig. 7 is a schematic view of a control circuit forming a part of the apparatus;

Fig. 8 is a fragmentary, horizontal section taken along line 8—8 of Fig. 2;

Fig. 9 is an enlarged, fragmentary, horizontal section taken along line 9—9 of Fig. 8;

15 Fig. 10 is a fragmentary horizontal section taken along line 10—10 of Fig. 5, and

Fig. 11 is an enlarged, fragmentary horizontal section taken along line 11—11 of Fig. 2.

Referring now to the drawings, an insulated

20 conductor 10 (Fig. 1) is advanced by a capstan 12 from a continuous extruding and vulcanizing machine 14, which extrudes and vulcanizes a covering over a suitable core, which may be a bare conductor, an insulated conductor or a group of insulated conductors. A coiler 20 advances the conductor 10 continuously from the capstan 12 over a counter 22 and past a distributor 24, which automatically distributes the jacketed conductor as the coiler 20 coils it into coils, illustrated by coils 26, 27 and 28. A cutter

25 30 automatically severs the jacketed conductor at predetermined points to separate the coils from one another. The individual coils are automatically conveyed from the coiler 20 by a turntable 32.

35 The coiler 20 includes a standard 40 (Fig. 2) having a bearing housing 42, in which are mounted thrust bearings 44—44 (Fig. 5) mounting a hollow journal 46 of a generally annular arbor 48 or drum, which has a bell-shaped guard portion 49 and is tapered slightly. A coiler motor 50, which is a standard electric motor of a variable speed type, serves to rotate the arbor 48 continuously. Endless roller chains 52—52

40 (Fig. 5), having guide rollers 51—51 projecting laterally therefrom into guideways 53—53, are mounted for movement in endless guideways 54—54 formed in the arbor 48. A series of sets of double-faced reel segments or separators, illustrated by reel segments 56—56, 57—57, 58—58

45 and 59—59, include link portions 62—62, which form every third link of the chains 52—52. The reel segments also are provided with relieved portions 64—64, which bear against straight portions of the chains 52—52 but which permit the

chains to move away therefrom as the chains and the links move around sharply curved portions 66-66 of the guideways 54-54, thereby permitting the chains 52-52 to curve sharply.

The distributor 24 (Fig. 1) is a conventional type of distributor and serves to distribute the jacketed conductor 10 in the space between the set of reel segments 56-56 and the set of reel segments 51-51, when these sets of reel segments are in positions shown in Fig. 5, and serves to guide the jacketed conductor to the coiler 20 only in that space.

A push rod 70 splined to the journal 46 carries a plurality of spring-pressed dogs 72-72 thereon and is fastened by a rotation-permitting, thrust-transmitting coupling 73 to a piston 74 (Fig. 2) mounted in a cylinder 76. When the piston 74 is moved upwardly, as viewed in Fig. 5, the dogs 72-72 engage two double-faced reel segments of the total number of reel segments fastened to each of the chains 52-52 and move the reel segments upwardly, which moves the chains 52-52 around the guideways 54-54 in directions which move the reel segments positioned on the outside of the guideways 54-54 downwardly. When the push rod 70 is moved downwardly again, the dogs 72-72 cam inwardly into the push rod 70 under the reel segments positioned between the guide rods 54-54 so that the reel segments and the chains 52-52 are not returned to their former positions. When the push rod 70 is moved downwardly, leaf springs 77-77 engage reel segments 79-79 to prevent the segments and chains from slipping back. When the push rod 70 is held in the position shown in Fig. 5, a shoulder 78 formed thereon and the dogs 72-72 prevent movement of the chains 52-52 along the guideways 54-54.

A bleeder-valve-controlled, four-way valve 80 (Figs. 2 and 6), of a well known type, controls the operation of the cylinder 76 and piston 74. After a predetermined length of the conductor 10 has been coiled between the set of reel segments 56-56 and the set of reel segments 57-57, the counter 22 (Fig. 1), which is a standard type of counter, momentarily closes a switch 82 (Fig. 7) thereof. This connects powerline conductors 84 and 85 through solenoid winding 88 of the valve 80 (Fig. 6) and a solenoid winding 90 (Fig. 7) of a bleeder-valve-controlled, four-way valve 92 (Fig. 2).

When the solenoid winding 88 is energized momentarily by the counter switch 82, it sets the valve 80 to supply air under pressure to the lower end of the cylinder 76, as viewed in Fig. 2. This moves the piston 74 and the push rod 70 (Fig. 5) upwardly, as viewed in Fig. 5, a distance sufficient to move the reel segments 56-56 to the positions occupied by the reel segments 51-51 in Fig. 5 and to move a set of reel segments 93-93 to the positions occupied by the reel segments 56-56 in Fig. 5. The conductor 10 passes between two adjacent reel segments 56-56, as they assume the positions formerly taken by the reel segments 51-51, and the coiling them is commenced between the set of reel segments 56-56 and the set of reel segments 93-93 to form a new coil.

The solenoid winding 90 (Fig. 7) is energized momentarily simultaneously with the energization of the solenoid winding 88 during the short period in which the switch 82 is closed, after which the counter 22 (Fig. 1) automatically resets to zero, and the switch 82 reopens. The winding 90 sets the valve 92 (Fig. 2) to direct air under pressure to the lower end of a cylinder 94, as viewed in Fig. 2, so that piston 96 is urged

upwardly to move a rod 98 upwardly. The rod 98 is connected by a thrust-transmitting, rotary coupling 99 to a slotted, tapered pan 100 and moves the pan 100 upwardly. The pan 100 has a journal 102 formed thereon, which is mounted rotatably in a bearing 104 formed in a rotating plate 106 of the turntable 32. A compression spring 108 normally urges the rod 98 and the pan 100 downwardly to hold the pan in engagement with a brake disc 110 carried by the plate 106 to prevent rotation of the pan 100 when in contact with the brake disc. However, when the valve 92 is actuated, as described hereinabove, and the pan 100 is moved upwardly, the pan 100 moves out of contact with the brake disc and moves a self-centering bevelled clutch facing 112 formed on the pan 100 into frictional engagement with a clutch facing 114 carried by the arbor 48, and as a result, the arbor 48 rotates the pan 100 therewith.

The distance the pan 100 is lifted by the piston 96 is much less than the distance through which the piston 74 is moved so that the pan 100 is moved into engagement with the arbor 48 during the initial portion of the upward stroke of the piston 74 and the movement of the chains 52-52 and the reel segments carried therewith. While the pan 100 is rotated with the arbor 48, the piston 74 completes its stroke and moves the set of reel segments 57-57 downwardly, as viewed in Fig. 5, to the positions occupied by the set of reel segments 58-58 in Fig. 5. At the same time the segments 58-58 move to the positions formerly occupied by segments 59-59. Since there is then no support for the coil 26, it drops upon the pan 100 by gravity.

At the piston 74 (Fig. 2) reaches the upper end of its stroke, a dog 118 carried thereby engages and closes a limit switch 120 (Fig. 7). The closing of the switch 120 completes a circuit to a solenoid winding 122 of the valve 80 (Fig. 6) and a solenoid winding 124 (Fig. 7) of a bleeder-valve-controlled, four-way valve 126 (Fig. 3), which is identical with the valve 80 and is associated with the cutter 30. This energizes the windings 122 and 124, and when the winding 122 is energized, it sets the valve 80 (Fig. 2) to supply air to the upper end of the cylinder 76, whereby the piston 74 is forced downwardly, as viewed in Fig. 2. This moves the dog 118 away from the switch 120 and this switch opens the downward movement of the piston 74, returns the push rod 73 to the position shown in Fig. 5, and the dogs 72-72 merely slide under the reel segments 59-59 and the set of reel segments 79-79 without moving the reel segments carried by the chains 52-52. The shoulder 78, the leaf springs 77-77 and the dogs 72-72 prevent lengthwise movement of the chains 52-52 until the next energization of the solenoid winding 88.

During the momentary energization of the solenoid winding 124 (Fig. 7), that is, while the switch 120 is closed, the winding 124 sets the valve 126 to supply air under pressure to the upper end, as viewed in Fig. 3, of a cylinder 128 and to exhaust air from the lower end thereof. This moves a carriage 130 of the cutter 30 downwardly, as viewed in Fig. 3, to the position it occupies in Fig. 11. The cutter 30 carries a blade 132 pivotally thereon, and the blade 132 is urged in a clockwise direction, as viewed in Fig. 3, by a compression spring 134. A blade 136 is connected pivotally to the blade 132 by a pin 138 and carries a follower 140 on an end thereof. A follower 140 is urged by a tension spring 141 against a cam

surface 142 formed on the carriage 130. The carriage 130 also is provided with a conductor-guiding surface 144, and stop pins 146 and 148, which limit movement of the blade 132 relative to the carriage 130.

When the carriage 130 reaches the position it occupies in Fig. 11, the tip of the blade 136 touches the outer periphery of the arbor 48 and is in a position in which a connecting loop 150 of the conductor 10 between the coil 26 and the coil between the segments 56-56 and 57-57 cannot slip between the blade 136 and the arbor 48 when the connecting loop 150 is moved past the carriage 30. The guide surface 144 guides the loop 150 between the blades 132 and 136 and as the loop 150 is carried further by the coiling head, it swings the blade 132 in a counterclockwise direction, as viewed in Fig. 11. This moves the blade 136 upwardly, and moves the cam follower 140 along the cam surface 142. As the cam follower 140 is moved along the cam surface 142, the blade 136 is swung in a clockwise direction in a cutting stroke, and the blades 132 and 136 are moved to the positions they occupy in Fig. 4 to sever the connecting loop 150. The compression spring 134, after the connecting loop 150 has been severed, moves the blade 136 back against stop pin 146, and the tension spring 141 and the return of the blade 132 return the blade 136 to its former open position.

When the carriage 130 is moved to its cutting position, as described hereinabove, a dog 152 carried thereby closes a normally open limit switch 154 to start a timer 156 of a well known type by energizing a clutch-actuating solenoid winding 160 thereof and energizing a timer motor 166 thereof through a normally closed switch 164. The timer motor 166 runs for a predetermined period of time, which is at least as great as the time necessary for the arbor 48 (Fig. 2) to make one complete revolution so that the connecting loop 150 is severed regardless of the position it occupied when the forward stroke of the cutter carriage 130 was completed.

After the connecting loop 150 (Fig. 3) has been cut and the period of time for which the timer 156 is set has expired, the timer opens the switch 164 and closes a switch 168 thereof. Opening of the switch 164 deenergizes the timer motor 166, but the clutch-actuating solenoid winding 160 is kept energized and the clutch (not shown) holds the switch 168 closed. When the switch 168 is closed, it completes circuits to a solenoid winding 170 of the valve 126 (Fig. 3) and a solenoid winding 172 (Fig. 7) of the valve 92 (Fig. 2).

When the solenoid winding 170 (Fig. 3) is energized, it sets the valve 126 in a condition in which air under pressure is supplied to the lower end of the cylinder 128, as viewed in Fig. 4. In this setting of the valve 126, air is exhausted from the upper end of the cylinder so that the carriage 130 is moved upwardly, as viewed in Fig. 4, to return the cutter 30 to its inactive position and hold it there. As the carriage 130 is so moved, the dog 152 is moved away from the switch 154, and the switch 154 then opens. This deenergizes the clutch-actuating solenoid winding 160 (Fig. 7) and the solenoid winding 170 and 172 so that the timer 156 resets to zero, thereby closing the switch 164 and opening the switch 168.

During the instant the solenoid winding 172 is energized, that is, during the time between the closing of the switch 168 and the opening of the switch 154, the winding 172 sets the valve 92 to supply air under pressure to the upper end of the

cylinder 94, as viewed in Fig. 2, and to exhaust air from the lower end of the cylinder 94 so that the ram 96 is moved downwardly to permit the compression spring 108 and the weights of the coil 26 and the pan 100 to force the pan 100 downwardly out of engagement with the clutch face 114 and into engagement with the brake disc 110. The brake disc 110 then stops the rotation of the pan 100 and the coil 26 carried thereon. During the downward movement of the ram 96, a pivotally mounted spring-pressed trip 173 engages a switch 174 and momentarily closes it to energize a relay winding 176 (Fig. 7) of a reset relay 177 (Fig. 8). As the ram 96 (Fig. 2) moves further downwardly, the trip 173 moves out of engagement with the switch 174 and this switch reopens. Since the trip 173 is pivotally mounted, it does not close the switch 174 during the upward movement of the ram 96.

During the momentary energization of the winding 176 (Fig. 7), the winding 176 moves an overcenter switch 178 to a closed position. Closing of the switch 178 completes the circuit to an electric motor 180 and a winding 182 of a latching solenoid 184 (Fig. 9). The winding 184 withdraws a tapered indexing pin 186 from a self-centering socket 188 formed in the plate 106 to permit the plate 106 to be rotated. By the time the winding 184 has released the plate 106 for rotation, the motor 180 starts to rotate the plate 106 in a counterclockwise direction, as viewed in Fig. 1. This moves the loaded pan 100 from under the coiling head 20 and moves an empty pan 189 identical therewith toward the position just left by the pin 100. Just before the plate 106 has rotated 90°, a dog 190 (Figs. 2 and 8) carried therewith moves into and out of engagement with a trip arm 192 of the reset relay 177 thereby tripping the trip arm 192. This tripping of the trip arm 192 opens the overcenter switch 178 (Fig. 7) to deenergize the motor 180 and the solenoid winding 182. Deenergization of the motor 180 permits the plate 106 to coast, and deenergization of the solenoid winding 182 releases the tapered indexing pin 186, which is urged upwardly, as viewed in Fig. 9, towards its indexing position, and the indexing pin 186 moves into a self-centering socket 194 formed in the plate 106 at a point 90° behind the socket 188 to lock the disc in this position. At this time, the empty pan 189 is directly below the coiling head 20 and the dog 190 is moved completely out of engagement with the trip arm 192 so that overcenter switch 178 (Fig. 7) may be reclosed during the next cycle of operation.

The coil 28 on a pan 196, which is moved into the position which the pan 189 occupies in Fig. 8, is tied and removed from the pan 196. When the new coil being formed between the reel segments 56-56 and the segments 93-93 (Fig. 5) has a predetermined length of conductor therein, the counter 22 (Fig. 1) initiates another cycle of operation identical with that described hereinabove.

In the apparatus described hereinabove, there is always one full coil on the coiler 20 adjacent to the beginning portion of a new coil which the coiler 20 is starting to coil. The severing action occurs below this full coil, which prevents the beginning portion of the new coil from flying loose from the coiler, as it might do if there were a severed end of the conductor in the beginning portion of the new coil. That is, by the presence of an intermediate coil between the coil 26 and the pan 100 being removed from the coiler 20 and the portion of

the conductor starting a new coil, the coiling is continuous and automatic. The intermediate coil, though having a loose end of the conductor, is prevented from unwinding on the coiler by the direction of rotation of the coiler, which keeps the loose end in place.

In the operation of the apparatus described hereinabove, the continuous extruding and vulcanizing machine 14 forms the insulated conductor 10, and the capstan 12 continuously advances the conductor through the machine 14. The coiler 20 continuously coils the conductor 10 and draws the conductor from the capstan 12 past the counter 22 and the distributor 24. When a sufficient length of the conductor 10 is coiled, the counter automatically starts the cycle of operation described hereinabove and the pan of the turntable 32 below the coiler 20 is moved upwardly into contact with the arbor 48 (Fig. 2) and starts to rotate therewith. The coils are moved downwardly one step to deposit the lowermost coil carried by the coiling head 20 on the pan being rotated with the arbor 48, and the coiler starts to wind a new coil. The cutter 30 (Fig. 3) cuts the connecting loop of conductor to separate the coil on the pan being rotated from the coil directly thereabove, that pan then is lowered out of engagement with the arbor 48, the turntable 32 is rotated 90° in a counterclockwise direction, as viewed in Fig. 1 and the operation described hereinabove is repeated.

The apparatus described hereinabove automatically winds the conductor 10 into a series of coils each having a predetermined length, severs the coils from each other and moves the coils into positions in which the coils may be tied so that an operator of the apparatus need only tie the coils to bind them and remove the tied coils from the turntable 32. The transition from the end of one coil to the beginning of a new coil is automatic and is accomplished without interruption in the coiling operation so that the continuous extruding and vulcanizing machine 14 need not be stopped to terminate one coil and begin another coil.

The coiler described hereinabove also is suitable for coiling other types of filamentary articles than insulated conductors, e. g., rope, twine, wire, etc., may also be coiled thereon.

What is claimed is:

1. A coiling apparatus, which comprises a rotatable drum, means for guiding filamentary material to the drum, a plurality of means carried by the drum for forming a plurality of coils of filamentary material upon the drum, means for effecting relative movement between the material-guiding means and the drum longitudinally of the drum to form a coil on the drum at each coil-forming means with portions of the material extending between the coils, and means for severing the portions of the material between the coils.

2. An apparatus for coiling filaments, which comprises a tapered, vertically mounted arbor, a plurality of sets of reel segments carried by the arbor in positions spaced longitudinally thereof, means for guiding the filament to a predetermined portion of the arbor to form a coil between two sets of the reel segments, means for moving the sets of reel segments along the arbor to move a coil formed between two of the sets away from said portion of the arbor to coil a new coil in said portion of the arbor, means for collapsing one of the sets of reel segments holding a formed coil to permit the coil to drop by gravity along the

arbor, and means for severing the latter coil formed from the remainder of the filament.

3. A coiling and severing apparatus, which comprises a rotatable arbor, a plurality of sets of separators, means for guiding a filament to a predetermined portion of the arbor, means for holding the sets of separators in spaced positions on the arbor, said holding means serving to hold a pair of said sets of separators in positions bracketing said space to which a filament is guided, means for rotating the arbor and the separators therewith to coil the filament between said pair of separators, means for shifting the separators longitudinally with respect to the arbor to bracket said space with a different two sets of separators, and control means for causing the shifting means to operate at predetermined intervals.

4. A coiling apparatus, which comprises a hollow arbor having at least one endless guideway extending longitudinally along the outer periphery thereof transversely over an end thereof, longitudinally along the inner periphery thereof and transversely to the outer periphery thereof, a plurality of reel segments mounted in side to side relationship in said guideway, and means for moving the reel segments along the guideway.

5. A coiling apparatus, which comprises a hollow arbor having at least one endless guideway extending longitudinally along the outer periphery thereof, transversely from the outer periphery thereof to the inner periphery thereof, longitudinally along the inner periphery thereof and transversely back to the outer periphery thereof, an endless chain mounted in the endless guideway, a plurality of reel segments mounted in side to side relationship in said guideway and carried by the chain, and means for moving the chain along the guideway.

6. A coiling apparatus, which comprises a plurality of sets of coil-separators, a plurality of endless chains mounted in radial planes for carrying the sets of separators in positions projecting from the chains at spaced points therealong so that a filament may be coiled between two adjacent sets of the separators, means for guiding a filament to the space between said adjacent sets of separators, means for revolving the chains to coil the filament between said adjacent sets of separators, and means for automatically moving the chains to move a full coil and to coil the filament between another two adjacent sets of separators.

7. A coiling apparatus, which comprises an arbor having at least one endless guideway extending along the outer periphery of the arbor longitudinally with respect to the arbor, transversely to the inner periphery of the arbor, longitudinally along the inner periphery of the arbor and transversely back to the outer periphery of the arbor, an endless chain mounted for movement in said guideway, a plurality of reel segments projecting from the endless chain at spaced positions thereon, means for serving a filament to a predetermined portion of the arbor, means for holding the chain in a position in which the chain holds two adjacent reel segments in positions bracketing said portion of the arbor to form a coil of the filament therebetween, and means operable when the predetermined length of the filament has been coiled between the two last-mentioned reel segments for moving the segments and the coil longitudinally on the arbor toward an end of the arbor and out of said predetermined portion of the arbor and for bracket-

ing said space with another pair of said reel segments to form a coil therebetween, said chains serving to carry the reel segments in positions extending perpendicularly to the chains so that the reel segments move from positions extending laterally with respect to the arbor when carried by the chain along the outer periphery of the arbor and extend parallel to the longitudinal axis of the arbor when carried by the chain along the portions of the guideway transverse to the longitudinal axis of the arbor so that coils may be removed from the end of the arbor.

8. A coiling apparatus, which comprises an arbor having at least one endless guideway extending along the outer periphery of the arbor longitudinally with respect to the arbor, transversely across an end of the arbor to the inner periphery of the arbor, longitudinally along the inner periphery of the arbor and transversely back to the outer periphery of the arbor, an endless chain mounted for movement in said guideway, a plurality of reel segments projecting perpendicularly from the endless chain at spaced positions thereon, said reel segments serving to collapse as they are moved over said end of the arbor, means for serving a filament to a predetermined portion of the arbor spaced from said end of the arbor, means for holding the chain in a position in which the chain holds two adjacent reel segments in positions bracketing said portion of the arbor to form a coil of the filament therebetween, means automatically operable when a predetermined length of the filament has been coiled between the two last-mentioned reel segments for moving the segments and the coil longitudinally on the arbor toward said end of the arbor and out of said predetermined portion of the arbor and for bracketing said space with another pair of said reel segments to form a coil therebetween, said chains serving to carry the reel segments in positions extending perpendicularly to the chains so that the reel segments move from positions extending laterally with respect to the arbor when carried by the chain along the outer periphery of the arbor to collapsed positions in which they extend parallel to the longitudinal axis of the arbor when carried by the chain over said end of the arbor so that coils may be removed from the arbor, and automatically and intermittently operable means for severing the conductor between coils thereof to separate the coils.

9. A coiling apparatus, which comprises a rotatable coiling head for coiling a filament into a series of coils and for moving the coils step by step along the coiling head after each coil is formed, means for severing the portion of the filament between two of the coils to separate these coils, said coiling head having a clutch member formed on an end thereof, a plurality of rotatable receiving elements, each of said receiving elements being provided with a clutch portion designed to engage the clutch portion on the coiling head, means for moving the receiving elements one at a time in alignment with the coiling head, means for pressing one of the receiving elements aligned with the coiling head toward the coiling head to cause engagement between the clutch portion of that receiving element and the clutch portion of the coiling head, means for moving a coil from the coiling head onto the last-mentioned receiving element, means for moving the last-mentioned receiving element away from the coiling head, means for braking the receiving element moved away from the coiling

head, and means for actuating the receiving-element-moving means when the last-mentioned receiving element is moved out of contact with the coiling head.

5 10. A coiling apparatus, which comprises a rotatable arbor, means for rotating the arbor, means for serving a filament to a predetermined coiling portion of the arbor, said coiling portion being spaced from an end of the arbor at least a distance equal to the length of the coiling portion, a plurality of sets of reel segments, means intermittently operable for moving the reel segments endlessly along the arbor, means for indexing the reel segments in positions bracketing the coiling portion of the arbor and for holding a coil previously formed in the coiling portion in a position spaced more closely to said end of the arbor than the coiling portion of the arbor, a receiving pan positioned adjacent to said end of the arbor, means for effecting non-rotating engagement between the receiving pan and the end of the arbor, means operable when a coil is completed at the coiling portion of the arbor for moving that coil and the coil preceding it along the arbor to move the foremost coil from the arbor to the receiving pan, a cutter operable after said movement occurs for severing a portion of the filament extending between the two coils to separate the coil on the receiving pan from the newly formed coil on the arbor, and means for disengaging the receiving pan from the arbor and for moving the pan out of alignment with the arbor.

15 35. 11. A coiling apparatus, which comprises a rotatable arbor, means for rotating the arbor, means for serving a filament to a predetermined coiling portion of the arbor, said coiling portion being spaced from an end of the arbor at least a distance equal to the length of the coiling portion, a plurality of sets of collapsible reel segments, means intermittently operable for moving the reel segments endlessly along the arbor, said coil segments being collapsible at said end of the arbor, means for indexing the reel segments in positions bracketing the coiling portion of the arbor and for holding a coil previously formed in the coiling portion in a position spaced closely to said end of the arbor than said coiling portion of the arbor, a receiving pan positioned adjacent to said end of the arbor, automatic means for effecting non-rotating engagement between the receiving pan and the end of the arbor, means automatically operable when a coil is completed at the coiling portion of the arbor for actuating the reel segment-moving means to move that coil and the coil ahead of it along the arbor to move the latter coil from the arbor to the receiving pan, a cutter actuated by the actuating means after said movement occurs for severing a portion of the filament extending between the two coils to separate the coil on the receiving pan from the newly formed coil on the arbor, and means operable after the operation of the cutter for disengaging the receiving pan from the arbor and for moving the pan out of alignment with the arbor.

20 45. 60. 65. 70. 75. 12. A coiling apparatus, which comprises a coiling head for forming a series of connected coils thereon from a continuous filament, a cutter movable to a position between two adjacent coils formed by the coil-forming means, said cutter including means operable by an interconnecting portion of the filament between the last-mentioned coils for severing said portion of the filament to separate the coils, and means for

removing from the coiling head a coil severed from the remainder of the coils.

13. A cutting and coiling apparatus, which comprises a rotatable arbor, means for rotating the arbor to coil a filament into a series of interconnected coils, a pair of shears, means for moving the shears to a position in which the shears are open and the tip of one of the shears touches the arbor at a point between two coils formed on the arbor, said arbor serving to move a portion of the filament connecting the last-mentioned coils into engagement with the shears, said shears being movable by said portion of the filament, camming means for closing the shears when the shears are moved by said portion of the filament to sever said portion, and means for moving the shears away from the arbor.

14. A coiling apparatus, which comprises a hollow arbor, a plurality of endless guideways spaced laterally around the arbor, a plurality of endless chains for movement in the endless guideways, a plurality of double-faced reel segments carried by the endless chains in substantially edge-to-edge relationship, a reciprocable member provided with a plurality of ratchet-feed means for engaging the reel segments to move the reel segments in one direction, said ratchet feed means serving to permit movement of the member in the other direction without moving the reel segments, and means associated with the ratchet feed means for preventing movement of the reel segments.

15. A coiling apparatus, which comprises a coiling head including an arbor for forming a series of coils therealong, means for pushing one at a time off the end of the arbor coils formed by the arbor, means for severing the coils, a turntable, a plurality of receiving pans carried rotatably by the turntable, means for indexing the turntable to position one of the receiving

pans in alignment with the arbor, means for moving the last-mentioned serving pan into non-rotatable engagement with the arbor, means for braking the last-mentioned receiving pan, means for moving the last-mentioned pan out of engagement with the arbor and into engagement with the pan-breaking means, and means for moving the last-mentioned receiving pan out of alignment with the arbor and for moving another serving pan into alignment with the arbor.

16. A coiling apparatus, which comprises a rotatable arbor having a clutch member formed on a free end thereof, a coil receiving element having formed thereon a clutch member complementary to the clutch member on the arbor and normally freely rotatable with respect to the arbor, means for transferring a coil from the arbor to the receiving element, means for braking the receiving element against rotation after receiving a transferred coil, means for moving the receiving element into and out of alignment with the arbor, and means for moving the aligned coil receiving element to engage the clutch thereof with the clutch member of the arbor.

ESTYLE D. HANSON.
